HUGO LENTZ, OF HALENSEE, NEAR BERLIN, GERMANY.

MID-EXHAUST STEAM-ENGINE.

1,118,661.

Specification of Letters Patent. Patented Nov. 24, 1914.

Application filed September 30, 1914. Serial No. 864,231.

To all whom it may concern:

Be it known that I, HUGO LENTZ, a citizen of the German Empire, and residing at Halensee, near Berlin, Germany, have invented certain new and useful Improvements in Mid-Exhaust Steam-Engines, of which the following is a specification.

My invention relates generally to so-called mid-exhaust steam engines, *i. e.* to steam engines having exhaust ports which are located in the middle of the cylinder and are controlled by the piston, and particularly to engines of this type having valve-stem guides which are disposed parallel to the cylinder and open into a common casing containing any suitable valve gear for actuating the valves. According to my invention this valve-gear casing constitutes part of the exhaust chamber, *i. e.* is connected with the same, so that there must be the same fall of pressure between the ends of the valve stems as in the halves of the cylinder located parallel thereto.

An important object of my invention is to provide that the valve stems can be more readily packed than heretofore and this is possible in my improved arrangement because the pressure at the ends of the guides of the stems is equal to the pressure of the exhaust and is thus so low that the clearances between the ends of the stems and the guides are filled by water of condensation. An additional advantage gained by this arrangement is a constant fall of pressure and, accordingly, a uniform distribution of temperature along the entire cylinder casting, thus not only along the cylinder itself but also along the valve-stem guides cast thereon, whereby stresses in the casting are effectively obviated.

To these ends my invention consists in the construction, arrangement and combination of parts described hereinafter and pointed out in the claims.

One illustrative embodiment of my invention and modifications thereof are represented by way of example in the accompanying drawing, wherein:

Figure 1 is a longitudinal section through a horizontal mid-exhaust steam engine of the type described, Fig. 2 is a like view of a modified form of valve-gear casing for a horizontal engine, and Fig. 3 is a like view of another form of valve-gear casing for a vertical engine.

Referring to the drawing, *a* designates the

steam cylinder in which the exhaust slots *b* are arranged in the middle and the admission ports *c* at the ends. The valve casings *d* are connected to the latter. These casings or boxes *d* contain the admission valve *e* which control the admission of the steam to the cylinder. The stems *f* of these valves are guided in holes *g* which are drilled parallel to the cylinder and open approximately over the exhaust slots *b* into a casing *h* containing the lay shaft *i* and the cam *k*. The ends of the valve stems *f* provided with anti-friction rollers bear against the cam and are driven by the latter against the action of the springs *l*. If desired, however, the valve stems may be actuated by any other suitable driving device.

The valve-gear casing *h* constitutes a part of the annular exhaust chamber *m* surrounding the exhaust ports *b* or is connected with this chamber; consequently, the ends of the valve stems nearest the casing *h* are subjected to the exhaust pressure, while the ends of the stems remote therefrom are subjected to the full pressure of the steam. Therefore the fall of pressure in the cylinder and in the guides of the valve stems is exactly equal, so that the stems can be readily packed and, in addition, no stresses can be set up in the casting in consequence of its being heated at one end more than at the other.

The invention can also be applied to such engines in which, for the purpose of lubricating the parts of the valve gear well, the casing *h* is separated by a wall *n* from the exhaust chamber and is partially filled with oil, as shown in Fig. 2. The free space over the oil is connected by an inserted tube *o* with the exhaust chamber *m*. The same arrangement can also be employed in a still more simple manner in vertical engines, as shown in Fig. 3. In this case it is only necessary to bore in the wall *n* a hole *p* which establishes the connection of the free space above the oil with the exhaust chamber.

I claim:

1. In a steam engine of the class described, the combination with a cylinder having admission ports at each end, and central exhaust ports, of admission valves having stems parallel to the cylinder, guide casings for the stems, means for actuating the valves in the proper alternation, and means for subjecting the casing ends adja-

cent to said actuating means to substantially the full pressure and temperature of the exhaust steam as delivered from the cylinder, to assist in packing the guide casings.

2. In apparatus of the class described, the combination with a cylinder having admission ports at each end and central exhaust ports, of admission valves, having 10 suitable stems, guide casings for said stems, an oil-containing casing inclosing the free ends of said stems and communicating with said guide casings and the exhaust ports, and means within the casing for actuating 15 the valve stems.

3. In apparatus of the class described the combination with a cylinder having admission ports at each end and central exhaust ports opening into a discharge conduit, admission valves, valve stems parallel to the 20

cylinder and having their free ends in proximity to each other and to a point in the conduit near the exhaust ports in the cylinder, guide casings for the stems, a casing inclosing the free ends of the stems and 25 guide casings and communicating with the conduit at said point, and means within the casing for actuating the valve stems; whereby the free ends of the valve stems and guide casings are subjected to substantially 30 the full pressure and temperature of the steam escaping at the exhaust ports of the cylinder.

In testimony whereof, I affix my signature in the presence of two witnesses.

HUGO LENTZ.
